(57) **CLAIM**

The ornamental design for a laser projector, as shown and described.

DESCRIPTION

FIG. 1 is a front perspective view of a laser projector showing our new design;

FIG. 2 is a front view thereof; and,

FIG. 3 is an enlarged view of the encircled portion labeled by reference numeral 3 in FIG. 2.

The broken lines depicting the remainder of the laser projector form no part of the claimed design.

1 Claim, 3 Drawing Sheets

FIG. 1

FIG. 2

FIG. 3
